JOSEPH O. CADIEUX, OF MERIDEN, CONNECTICUT, ASSIGNOR TO CONNECTICUT TELEPHONE & ELECTRIC CORPORATION, OF MERIDEN, CONNECTICUT, A CORPORATION OF DELAWARE

GAS TUBE TRANSFORMER AND SOCKET

Application filed September 11, 1930. Serial No. 481,161.

My invention relates particularly to apparatus for the use of electrically actuated lamps of the gas tube type employing transformers. The main object is to provide a simple compact arrangement of transformer and socket. In such constructions the voltage available is usually of the order of 100 to 200 volts and the lamps themselves require, as a usual thing, a very much higher voltage. The tubes being fragile and of a much shorter life than the transformers, it is highly desirable that provision be made for readily removing and replacing the lamps. I have accordingly endeavored to arrange a combination of transformer and socket suitable for the use of such tubes. One object is to provide an inexpensive but compact device for this purpose. Another object is to provide a construction in which there is practically no possibility of short circuiting and a minimum possibility of accidental engagement with the high potential terminals.

In carrying out the invention I provide a housing preferably of insulating material adapted to contain the transformer. This housing has embodied as a part of it sockets or clips adapted to receive the terminals of a lamp tube. The contacting parts of the sockets are so protected or guarded that there is little possibility of accidental contact with them. Other advantages will appear from consideration of the following specification and the accompanying drawing.

Fig. 1 is a sectional view of a device embodying my invention and showing a lamp tube in place.

Fig. 2 is a section and plan on the plane of the line 2—2 of Fig. 1.

Fig. 3 is a sectional view of a modified form of construction and showing the ends of the tube inserted in the sockets.

The transformer 5 may be of any suitable type having input leads 6—6 and output leads 7—7. This is enclosed in a housing preferably of insulating material and which may conveniently be made of the two parts 8 and 9, one of which serves as a holder or body portion and the other of which serves as a cover. The transformer may be impregnated

and filled with a suitable insulating composition, 10.

One of the parts of the housing is provided with socket portions 11, in which are mounted spring terminal contact or clip portions 12, secured for instance, by tubular rivets 13, to which are soldered or otherwise suitably secured the output leads 7—7 of the transformer. These socket portions 11 are large enough to accommodate terminal clips 12 and permit insertion of the ends of the tube 14, which contains the luminous gas and has electrodes 15 and external terminal portions 16. The ends of the tube are adapted to be plugged in to the clips or removed as occasion may require.

To prevent accidental engagement with the terminal clips, I prefer to provide a guard-plate 17, of insulating material, having openings 18 just large enough to permit the insertion of the ends of the tube and yet small enough to prevent one from inserting his fingers or otherwise accidentally engaging the high potential clips.

It will be seen that this construction constitutes a self contained transformer and socket arrangement capable of serving as a support for the gas tube. It will be understood of course that the size and spacing of the sockets 11, will depend upon the size of the lamp tube and the spacing of the ends of the tube. The same transformer may be employed for different sizes of tubes by simply providing a cover, 9, having sockets of the proper size and spacing. Of course the openings 18 in the guard-plate, 17, should be dimensioned and spaced to correspond with the sockets.

In the form of construction shown in Fig. 3, the sockets 11' project outwardly from the cover portion 9 of the housing and are provided with guard caps or rings 17'.

The housing for the transformer can be conveniently formed of molded insulation, with the parts protected and secured together so as to prevent leakage. It will be seen that the construction is simple and yet affords a convenient means for mounting a gas lamp tube. The invention permits of changes in the tube, for instance for the change of letter, signs, and so forth. Obviously a number

of these small transformer socket units may be employed to build up any desired word or sign, each unit constituting a support and current supply for a single tube. It should 5 be understood, however, that the invention is not limited to the use of tubes representing single letters but might be used with tubes which constitute words or other indicia.

I claim:

- 10 1. A transformer and socket for gas tubes comprising a housing having spaced sockets open at one end, contact clips mounted in said sockets at their closed ends and adapted to hold the ends of an inserted tube, and a transformer in the housing having its output leads connected to said clips.
- 15 2. The combination of a transformer, an insulating member at least partially enclosing the transformer, said member having spaced sockets open at their outer ends, and spring terminal clips mounted on the inner ends of the sockets and electrically connected with the output leads of the transformer.
- 20 3. A transformer socket construction for gas lamps comprising a transformer, an insulating member having spaced pockets within the transformer and spring terminal clips mounted in the pockets at their lower ends and connected to the output leads of the transformer.
- 25 4. A transformer socket construction for gas lamps comprising a transformer, an insulating member having spaced pockets within the transformer and spring terminal clips mounted in the pockets at their lower ends and connected to the output leads of the transformer and means for guarding the clips in the pockets.
- 30 5. A device of the character described consisting of a transformer formed with primary and secondary coils having molded insulating material therebetween, spaced pockets formed in said insulating material interiorly of said coils, the opened ends of said pockets being substantially flush with the top of said coils and insulating material, an insulating member enclosing the top of said coils and insulating material and conforming to the shape of said pockets, a spring terminal clip mounted in each of said pockets on the bottom closed end thereof, means including an eyelet for connecting each of said clips to the output circuits of said secondary coils, and an insulating guard plate positioned over the opened ends of said pockets and provided with openings to permit the passage of the ends of an inserted tube.

JOSEPH O. CADIEUX.
